UNITED STATES PATENT OFFICE.

JOSEPH HERRBURGER, OF PARIS, FRANCE.

ACTION-RAIL FOR UPRIGHT PIANOS.

SPECIFICATION forming part of Letters Patent No. 355,394, dated January 4, 1887.

Application filed June 4, 1886. Serial No. 204,111. (No model.) Patented in France February 19, 1885, No. 167,145, and in England February 24, 1885, No. 2,497.

To all whom it may concern:

Be it known that I, JOSEPH HERRBURGER, of Paris, France, but temporarily a resident of the city of New York, county and State 5 of New York, have invented a new and Improved Action-Rail for Upright Pianos, (for which I have obtained English Letters Patent No. 2,497, February 24, 1885, and French Letters Patent No. 167,145, February 19, 1885,) 10 of which the following specification is a full, clear, and exact description.

This invention relates to a metallic action-rail for upright pianos, so constructed that the various pieces composing the action have a 15 free play, while the rail itself occupies but a minimum amount of space. The rail is so constructed that two styles of action may be attached to it, one style having the catch beneath and the other at the side of the hammer-butt.

The invention consists in the elements of improvement hereinafter more fully pointed out.

In the accompanying drawings, Figure 1 is 25 a sectional side view of one style of an action provided with my improved action-rail. Fig. 2 is a similar view of the second style of action.

The letter *a* represents the key, *b* the bottom rail, *c* the jack, *d* the hammer-butt, *e* the hammer, and *f* the hammer-rest rail, of an 30 upright-piano action, all as usual. *A* is the action-rail connected to the butt-flange *g*, and also to the bottom rail, *b*, by means of fork *h*. This action-rail is made of iron or other metal, 35 and is of uniform width, excepting at the top, where it is tapering.

The peculiar shape of the action-rail is shown in both figures of the drawings, and is as follows: *A* tapering horizontal top section, 40 *i*, joins a downwardly-extending straight section, *j*, which terminates in a backwardly-curved portion, *k*. This portion *k* connects with a straight section, *l*, having a forwardly-projecting horizontal flange, *m*, which in turn 45 is provided with a downward extension, *n*. Thus it will be seen that the rail has three

principal vertical or nearly vertical sections, *j l n*, of which the upper and lower sections are in line, while the central section is thrown backward, and is joined to the upper section 50 by a curved portion, and to the lower section by a straight portion.

The uppermost horizontal portion, *i*, of the action-rail serves, as has already been stated, for the attachment of the butt-flange *g*. To 55 the upper straight section *j* there is attached the support *o* of the regulating-rail *p*. The cavity formed by placing the section *l* backward is utilized in the construction shown in Fig. 1, for the reception of catch *q*, attached 60 to the hammer-butt *d* and co-operating with the back check, *r*. With this construction the curved portion *k* of the action-rail corresponds to the curve of catch *q*, and permits the free motion of such catch. The seat formed by the 65 parts *m n* is designed for the reception of the fork *h*, which is screwed to section *n*, and bears against section *m*, as shown.

In Fig. 2 the form of the rail *A* has the same advantages as in Fig. 1, with the exception 70 that the catch *q* need not be cleared by the rail. In this figure the part *l* is set back so as to bring the section *m* in proper position above the fork *h*.

I claim as my invention--

1. The combination of key *a*, bottom rail, *b*, jack *c*, hammer-butt *d*, hammer *e*, and butt-flange *g*, with action-rail *A*, having two forwardly set upper and lower sections, *j n*, and a central backwardly-set section, *l*, substantially 80 as specified.

2. As a new article of manufacture, an upright-piano-forte action-rail, *A*, composed of tapering horizontal section *i*, straight vertical section *j*, curved section *k*, straight vertical 85 section *l*, straight horizontal section *m*, and straight vertical section *n*, substantially as specified.

J. HERRBURGER.
